UNITED STATES PATENT OFFICE.

WILLIAM A. PEARSON, OF SCRANTON, PENNSYLVANIA, ASSIGNOR TO THE BOIES STEEL WHEEL COMPANY, OF PENNSYLVANIA.

PRESS FOR FORGING CAR-WHEELS.

SPECIFICATION forming part of Letters Patent No. 449,824, dated April 7, 1891.

Application filed May 14, 1890. Serial No. 351,830. (No model.)

To all whom it may concern:

Be it known that I, WILLIAM A. PEARSON, of the city of Scranton, county of Lackawanna, and State of Pennsylvania, have invented 5 certain new and useful Improvements in Presses for Forging Car-Wheels, whereof the following is a specification, reference being had to the accompanying drawings, in which—

Figure 1 is a side view of the hydraulic 10 press. Fig. 2 is a vertical section of the upper and lower die and the annular contracting matrix. Fig. 3 is a view from above of the contracting matrix. Fig. 4 is a top view, and Fig. 5 is a side view, of the ingot after 15 forging. Fig. 6 is a top view, and Fig. 7 is a side section, of the wheel-center as completed. Fig. 8 shows more in detail the parts marked *g* and *j*, Fig. 3. Fig. 9 is a vertical section of the upper and lower die and the annular 20 contracting matrix, showing a modification of the method of operating the same. Figs. 10 and 11 are respectively a half of a plan view and a side elevation of the modification shown in Fig. 9.

Fig. 1 shows a large and strongly-constructed hydraulic press, the details of which it is 25 unnecessary to describe.

B is the lower and fixed die resting upon a bed-plate. The upper and movable die is 30 fixed upon the piston *F*.

C is an annular contracting matrix surrounding the upper die, fixed to the independent pistons *D D*, and capable of being lowered either by itself or in conjunction 35 with the upper die. This matrix is shown in section in Fig. 2. It consists of three rings, one above the other, strongly bolted together. The upper and lower ring have an inside diameter precisely that of the upper and lower 40 dies, around which they fit closely. The inside diameter of the central ring is greater than that of the other two, and its inside surface presents a beveled edge tapering upward. (Seen in section 1 at *h h* in Fig. 2.) 45 Its height is somewhat greater than the depth of the periphery of the wheel-center which it is desired to forge. Within this central ring are a number of segments *e e*. These segments have a height somewhat less than that 50 of the central ring, and consequently are capable of vertical play within the same. The

spaces between the movable segments are filled with wedge-shaped pieces or projections *j j*, having a depth equal to that of the movable segments and fixed around or forming 55 part of the upper part of the central ring, so that they extend down only as far as the dotted line *y y* in Fig. 2. The spaces between the bases of these wedge-shaped pieces form vertical slots *k*. At the back of each segment 60 is a T-shaped lug *g*, Fig. 3, which is dovetailed into and runs in the slot *k*. The back of each of the segments is beveled to correspond with the bevel of the central ring of the matrix, so that when they are in their 65 lowermost position their inner edges form a circle of greater diameter than when they are at the upper part of their play. When they are in this latter position, their inner edges form almost a complete circle, (indicated by 70 the dotted lines in Fig. 3,) having a diameter almost that of the wheel-center which it is desired to form. It will also be seen that when they are in this latter position their upper and lower edges will exactly correspond with 75 those of the wedge-shaped pieces *j j*, which consequently will exactly fill the interstices between them.

The operation of the press is as follows: A casting or ingot of approximately the shape 80 of the wheel-center is heated and placed upon the lower die. The contracting matrix is then lowered until it surrounds the upper portion of this die and the movable segments in their lower position rest upon the lower die, completely inclosing the ingot. The upper die is then lowered. As soon as its face presses 85 upon the top of the wedges *j j* the matrix is forced to descend with it, and the movable segments being prevented from descending 90 farther by the lower die commence to contract. The result is that pressure is simultaneously applied to the top, bottom, and sides of the ingot. Other methods of actuating the segments *e* may be employed without departing 95 from the spirit of my invention, which contemplates the simultaneous contraction of these segments along with the descent of the upper die.

In Figs. 9, 10, and 11 I have shown a modification of my device, whereby the movement of the segments is obtained by independent

hydraulic pressure. As before, *ee* represent the segments, each of which is mounted upon the end of a horizontal plunger *m*, the head *n* of which plays within the hydraulic cylinder *t*. These hydraulic cylinders are disposed radially around the entire circumference of the die. Both exits *p q* of all of these hydraulic cylinders are respectively connected with the circular pipes *r s*, by means of which the simultaneous actuation of all the segments *e* and under precisely the same pressure is secured. The segments *e* are no longer capable of any vertical movement, as in the device heretofore described, their simple horizontal motion now effecting all that was previously accomplished by the combined motion.

When the forging is complete, the center of the hub may be punched out while the forging is still in the matrix, the punch being operated by the piston-head. The completed forging is shown in Figs. 4 and 5, Figs. 6 and 7 showing the wheel-center after it is turned off to receive the tire.

Having thus described my invention, I claim—

1. In a press for forging, the combination of the upper and lower dies and a series of circumferentially-arranged radially-acting segments adapted to contract simultaneously with the compression of the upper and lower dies, substantially as described.

2. In a press for forging, the combination of the dies A B, the annular matrix C, contain-

ing the segments *e*, adapted to be caused to contract simultaneously with the compression of the dies, substantially as described.

3. In a press for forging, the combination of the dies A B, the annular matrix C upon the independent pistons D D, containing the segments *e*, adapted to be caused to contract simultaneously with the compression of the dies, substantially as described.

4. In a press for forging, the combination of the dies A B, the annular matrix C, having on its inside the beveled edge *h*, and the segments *e*, playing against that edge, substantially as described.

5. In a press for forging, the combination of the dies A B, the annular matrix C, having on its inside the beveled edge *h*, and the segments *e*, playing against that edge, the wedge-shaped blocks *j* between the segments, the slots *k* between these blocks, and the lugs *g* upon the back of the segments dovetailed into said slot, substantially as described.

6. In a press for forging, the combination of the dies A B and a series of circumferentially-arranged segments *e*, each actuated by a horizontal hydraulic cylinder *t*, and means, substantially as described, whereby the simultaneous action of all said cylinders *t* may be secured, substantially as described.

WILLIAM A. PEARSON.
